LIQUID FUEL BURNER

Harry Cowan, Akron, Ohio, assignor to The Babcock & Wilcox Company, Newark, N. J., a corporation of New Jersey

Application October 24, 1936, Serial No. 107,364

6 Claims. (Cl. 285—23)

My present invention relates to the construction and operation of liquid fuel burners, and more particularly to liquid fuel burners having two separate streams of fluid under pressure passing therethrough.

The main object of my invention is to provide an improved liquid fuel burner construction of the type described having special provisions for permitting relative movement of the passage-forming parts while preventing leakage between the passages. A further object is to provide improved coupling provisions of the quickly detachable type for connecting the burner fluid passages to corresponding sources of fluid supply. Another object is to provide a fluid atomizing liquid fuel burner having simple and effective means for cleaning the liquid fuel passage.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described preferred embodiments of my invention.

Of the drawings:

Fig. 1 is a fragmentary elevation mainly in section of a liquid fuel burner constructed in accordance with my invention;

Fig. 2 is a bottom view of a portion of the coupling;

Fig. 3 is a view taken on the line 3—3 of Fig. 1 showing the outer end of the coupling with the gasket in position;

Fig. 3A is a vertical section through the gasket;

Fig. 4 is a vertical section taken on the line 4—4 of Fig. 1;

Fig. 5 is an end view of the burner body; and

Fig. 6 is a sectional elevation of a modified body construction.

My invention is especially adapted for use in liquid fuel burners of the fluid atomizing type in which jets of steam or air at a higher temperature and/or pressure than the liquid fuel are caused to impinge upon the liquid fuel immediately prior to its entry into the furnace for the purpose of atomizing the same and promoting combustion thereof. A liquid fuel burner of this type is shown and comprises an elongated inner barrel or pipe 10 which serves as the fuel oil passage and an outer surrounding barrel or pipe 11 with the annular space therebetween serving as a steam passage. The inner barrel 10 is threaded at its

inner or discharge end into a sprayer head 12, as indicated at 13. The sprayer head abuts the discharge end of the outer barrel 11 and the inner and outer barrels are fixed in relative position at their discharge ends by an end cap 14 fitting over the sprayer head and threaded on the outer barrel. A series of passages is provided in the sprayer head and in an associated sprayer plate 15 for the steam and oil arranged as shown in U. S. Patent 1,980,132 for effecting impingement of the steam on the oil issuing from the oil passages and providing a discharge of atomized oil and steam through the spray nozzle 16. The outer barrel is surrounded by a tubular distance piece 17 suitably supported with respect to the furnace opening and threaded at its inner end to support an annular impeller plate (not shown).

In liquid fuel burners of this type both the oil and steam are under pressure with the steam at a higher pressure and temperature than the oil. The inner barrel is thus contacted at its inner and outer sides by fluids of different temperature, while the outer barrel is contacted by the higher temperature fluid only. The barrels 10 and 11 when the burner is in operation thus normally have different degrees of longitudinal expansion. For the proper functioning of such burners, it is important that the oil and steam shall not mix until each issues from the separate exit orifices provided in the sprayer head, and to this end it is necessary to prevent leakage of steam into the oil passage, or of oil into the steam passage, leading to the sprayer head. In accordance with my invention the barrels are relatively fixed in position or rigidly connected at their discharge ends by the construction heretofore described and are substantially free to expand and contract relative to one another at their outer ends without leakage from one passage to the other.

The liquid fuel burner is supported inside of the distance piece by a body member 20 at the outer end having a steam passage 21 and oil passage 22 separated by a central partition 23. The barrel members fit into a tubular extension 24 of the body member with the inner barrel 10 extending beyond the outer barrel and firmly fixed in position at its outer end in an opening formed in the upper part of the partition 23, as for example, by a fluid tight threaded engagement in the partition as indicated at 26. Oil from the body passage 22 is thus supplied to the inner barrel 10. Steam from the passage 21 passes around the outer end portion of the barrel 10 before entering the outer barrel 11. The barrel 10 is thus rigidly connected to associated parts at its op-

posite ends and forms a leak-proof wall between the two fluid passages. Any movement of the outer barrel 11 relative thereto is provided for by forming an expansion or slip joint between the outer end of the barrel 11 and the body extension 24. As shown, the outer end of the barrel 11 has a sliding fit in the body extension 24. Steam packing 27, a follower ring 28, and a gland 29 threaded into the body extension to hold the ring 10 and packing in position, collectively close the joint between the outer barrel and the body. By having the outer end of the inner barrel with a fixed fluid-tight connection with the body and the described joint between the outer barrel and the body, any steam leakage through the joint will be to atmosphere, and not into the oil passage with its attendant disadvantages. Any such leakage will be quickly observed by the operator with the described position of the joint. No leakage of fluid from one passage to the other is possible with the inner barrel which separates the passage free of leak joints, and freed by the outer barrel expansion joint of expansion stresses.

The fuel burner passages are connected to suitable sources of supply and the parts held in their assembled positions by means of a coupling 30 of the quickly detachable type. The coupling has a short tubular section 30a threaded on the outer end of the distance piece and held in position by a set screw 31 which fits into a longitudinal slot 32 formed in the distance piece. The body of the coupling contains a pair of superposed steam and oil passages 33 and 34 respectively which communicate with suitable sources of supply through laterally extending pipe connections 35 and 36 respectively at opposite sides of the coupling, as shown in Figs. 1 and 4.

A fluid-tight connection is formed between the coupling passages 33 and 34 and the lower ends 40 of the body passages 21 and 22 respectively. As shown, the end of the body and the end of the coupling which are to be connected are made circular. The coupling end has a peripheral circular lip 42 which fits into a circular groove 41 in the end of the body to center one with respect to the other, and to provide a circumferential groove to hold a gasket 43 shown in Fig. 3A, between the two parts. This gasket which is preferably of soft copper, is a flat disc 44 with two openings in axial alignment with the passages 33 and 34. Ring members 37 of U-shaped cross-section are formed in each disc opening to provide raised sealing surfaces around the edges of each disc opening which contact with the faces of the coupling and the body surrounding the oil and steam passages therein. A dowel pin 38 on the coupling fits through an opening 39 in the gasket into a corresponding recess in the body to hold the passages and gasket openings in registering relationship.

To insure a fluid-tight contact between the body and coupling between which the gasket is located, a yoke member 50 is pivotally mounted on the coupling adjacent the portion thereof contacting with the body member. The legs of the yoke member extend around the lower end of the body member and unite to form an internally threaded hub 51. A T-handle set screw 52 is threaded through the hub 51 and provided with a conical end portion 53 adapted to fit into a correspondingly shaped recess 54 formed in the body at the same level as the pivot axis of the yoke. As shown, a horizontal plane through the screw axis, the yoke pivots and the middle of the yoke legs will pass through the center of the

gasket and there will be one fluid passage on each side of that plane sealed by the raised sealing surfaces of the gasket. When the screw is tightened a force is developed along this plane, which forces the ends of the coupling and body toward each other, and compresses the gasket ring about the two passages equally, without any tendency to force the axes of the barrels 10 and 11 away from the axis of the distance piece 17. This locks the burner in position and at the same time prevents any leakage from one passage to the other at the joint between the coupling and the body.

With this arrangement of the parts the set screw 52 can be loosened sufficiently to allow the yoke to swing downwardly to a vertical position. The burner may then be readily removed and disassembled for inspection, cleaning or repair purposes, or for replacement by withdrawing the body, barrels, and associated parts outwardly through the distance piece. For replacing the burner the operations are reversed.

In Fig. 6 an additional element is illustrated by means of which the oil passage can be cleaned without removal or disassembling of the burner. In this arrangement a by-pass passage 60 controlled by a valve 61 is formed in the body partition 23 between the steam passage 21 and the oil passage 22. In cleaning the oil passage, the supply of oil is cut off and the valve 61 opened to allow steam from the passage 21 to flow through the by-pass passage 60 into the inner barrel 10. When this is done the temperature of the parts normally contacted by oil is changed and expansion is different but by my construction with the expansion joint no harm results after normal operation is resumed.

While in accordance with the provisions of the statutes I have illustrated and described herein the best forms of my invention now known to me, those skilled in the art will understand that changes may be made in the form of the apparatus disclosed without departing from the spirit of the invention covered by my claims, and that certain features of my invention may sometimes be used to advantage without a corresponding use of other features. In the claims, the word "steam" is intended to generically cover any suitable atomizing fluid.

I claim:

1. A liquid fuel burner comprising a body member having separate fluid passages therein, a coupling member having separate fluid passages therein adapted to register with the adjacent end of said body passages, said coupling and body having their adjacent ends provided with cooperating peripheral lip and groove portions and forming a circular seat, a gasket in said seat having openings therein arranged to register with said coupling and body passages, and yoke means arranged to detachably hold said coupling, gasket, and body in fluid-tight engagement.

2. A liquid fuel burner comprising a body member having separate fluid passages therein, a coupling member having separate fluid passages therein adapted to register with the adjacent end of said body passages, said coupling and body having their adjacent ends provided with cooperating peripheral lip and groove portions arranged to form a circular seat, a metallic gasket in said seat having openings therein arranged to register with said coupling and body passages, said gasket having raised sealing surfaces about said openings, and yoke means arranged to de-

tachably hold said coupling, gasket, and body in fluid-tight engagement.

3. A liquid fuel burner comprising a body member having separate fluid passages therein, a coupling member having separate fluid passages therein adapted to register with the adjacent end of said body passages, said coupling and body having their adjacent ends provided with cooperating peripheral lip and groove portions and forming a circular seat, a gasket in said seat having openings therein arranged to register with said coupling and body passages, a dowel member arranged to align said coupling, gasket, and body with their passages in register, and yoke means arranged to detachably hold said coupling, gasket, and body in fluid-tight engagement.

4. A steam atomizing liquid fuel burner comprising a body member having separate vertically spaced liquid fuel and steam passages therein, a coupling member having separate liquid fuel and steam passages therein adapted to register with the adjacent end of the corresponding body passages, said coupling and body having their adjacent ends provided with cooperating peripheral lip and groove portions and forming a circular seat, a metallic gasket in said seat having openings therein arranged to register with said coupling and body passages, said gasket having raised sealing surfaces about said openings, a dowel member arranged to align said coupling, gasket, and body with their passages in register, and yoke means arranged to detachably hold said coupling, gasket, and body in fluid-tight engagement.

5. A liquid fuel burner comprising an elbow-shaped body member having separate vertically spaced fluid passages therein, a coupling member

having separate vertically spaced fluid passages therein adapted to register with the adjacent end of the corresponding body passages, said coupling and body having their adjacent ends provided with cooperating peripheral lip and groove portions and forming a circular seat, a gasket in said seat having openings therein arranged to register with said coupling and body passages, a yoke member pivotally mounted on said coupling and extending around said body, and a screw on said yoke member adapted to seat in said body, said yoke member pivot axis and said screw axis being in a horizontal plane passing through the center of said gasket when the parts are in fluid-tight engagement.

6. A liquid fuel burner comprising a body member having separate vertically spaced fluid passages therein, a coupling member having separate vertically spaced fluid passages therein adapted to register with the adjacent end of the corresponding body passages, said coupling and body having their adjacent ends provided with cooperating peripheral lip and groove portions and forming a circular seat, a gasket in said seat having openings therein arranged to register with said coupling and body passages, said gasket having raised sealing surfaces about said openings, a dowel member arranged to align said coupling, gasket, and body with their passages in register, a yoke member pivotally mounted on said coupling and extending around said body, and a screw on said yoke member adapted to seat in said body, said yoke member pivot axis and said screw axis being in a horizontal plane passing through the center of said gasket when the parts are in fluid-tight engagement.

HARRY COWAN.
